UNITED STATES PATENT OFFICE.

ALBERT F. LESLER, OF NEW YORK, N. Y.

PAPER-DISPENSER.

1,198,561.

Specification of Letters Patent. Patented Sept. 19, 1916.

Application filed April 24, 1913, Serial No. 763,326. Renewed February 17, 1916. Serial No. 78,964.

To all whom it may concern:

Be it known that I, ALBERT F. LESLER, a citizen of the United States, and a resident of the city of New York, borough of the Bronx, in the county and State of New York, have invented a new and Improved Paper-Dispenser, of which the following is a full, clear, and exact description.

This invention relates to improvements in paper dispensing devices, and particularly to improved devices for dispensing in a sanitary manner paper which is required for individual use, and has for an object the provision of a structure which will cause or permit the dispensing of separate pieces of paper to different individuals without permitting any contact of the paper except by the person receiving the same.

A further object of the invention is to provide a paper dispensing device arranged with a pad or tablet of paper therein, and formed with notches and a discharge opening, together with holding means for the paper which will allow only one sheet of paper to be discharged at a time, and also allow contact only with the piece of paper being discharged, so that the paper dispensed will be maintained in a pure, sanitary condition.

In carrying out the objects of the invention, paper of various kinds and for various purposes may be dispensed or delivered, as for instance the sanitary paper for water closets. When dispensing pieces of paper of this kind, a suitable housing or closure is provided, having a slot or opening at one end merging into a pair of notches near the sides of the housing. The paper is arranged in a pad formed with one piece lying directly on top of the other, and with the ends exposed at the slot and notches, whereby the thumb of an operator passed through the notches may engage the top piece of paper and move the same through the delivery notch. The paper is held in the receptacle by a pair of retaining clips arranged in line with the thumb notches so as to permit a direct pull against the clips and thereby permitting the easy cutting or tearing of the paper by the clips. Also arranged substantially centrally of the housing is a spring clip for engaging the paper at a certain point for resiliently holding the same in place.

A practical embodiment of the invention is represented in the accompanying draw-

ings forming a part of this specification, in which similar characters of reference indicate corresponding parts in all the views.

Figure 1 is a front elevation of an embodiment of the invention; Fig. 2 is a view similar to Fig. 1 except that the top of the housing has been removed; Fig. 3 is a detail fragmentary view through Fig. 1 on the line 3—3; and Fig. 4 is an enlarged perspective view of one of the retaining clips.

Referring to the accompanying drawings by numerals, 1 indicates the retaining box as a whole, designed to contain a pad 2 of paper, cloth or other flexible material. The box 1 may be of any size or shape, and also of any desired material, without departing from the spirit of the invention. Preferably, however, the top 3 is hinged or pivotally connected in any desired manner to the end 4 so as to be moved back to the position shown in Fig. 2, or to open the housing 1 sufficiently to insert a new pad 2. The pad 2 comprises any desired number of strips or pieces of paper, each piece being independent and loosely fitting into the housing or box 1. The pad 2 is held in place by a pair of clips 5, shown in detail in Fig. 4, wherein the body 6 thereof is formed comparatively thin and is arranged in the housing 1 edgewise to the movement of the paper so as to cut or tear the paper easily when any of the pieces of paper are pulled by the thumb, as shown in Fig. 3. Preferably a thumb is inserted in both of the notches 7 and 8, so as to pull the paper perfectly straight and against the fastening clips 5, the notches 7 and 8 being in alinement with clips 5. The top of the clip 5 is bent over at 9 to form a head, while the bottom is divided and bent for forming retaining arms 10 and 11, these arms extending through the back of the housing 1 so as to properly anchor the clips in place. As clearly shown in Fig. 1, the top 3 falls short of the end 12 so that a slot or opening 13 is presented through which the piece of paper in pad 2 is forced, as shown in Fig. 3. Ordinarily the end of the piece of paper from pad 2 strikes against end 13 and then forms a loop 14 (Fig. 3) which loop extends to a position outside of the opening. This is grasped and an entire piece of paper is removed, which may then be used in the usual manner.

In forming the pad 2, the various pieces of paper of which the same is composed, is provided with an opening 15 having a tip

- 16 projecting therein. The tip 16 is pressed by a suitable spring 17, which has its ends extending through the back 18 of the housing 1, the same being bent over against the back, and part of the front portion of spring 17 being likewise bent against the front of the back so as to hold the spring properly in place and in position for continually pressing against tip 16.
- 10 The spring 17 is arranged to project through opening 18 and press against the tongue 16 in order to keep the sheets of paper from buckling when being removed. If the sheets of paper were formed without opening 18, spring 17 would not be necessary, but when a sheet of paper has an opening of an appreciable size arranged substantially centrally thereof it will buckle, and twist and pull from one end. A sheet of paper of this kind if supported freely in the air so as to hang in a vertical position would buckle or turn so that part of the sheet will move out of the plane of the remaining portions of the sheet. Buckling or twisting of the sheet would entangle the sheet being removed with the remaining sheets unless means were provided for preventing such buckling. The spring 17 is arranged so as to properly press against the lower portion 30 of the sheet while permitting the upper part to freely slide thereover.
- When it is desired to arrange the device in place for use, nails, hooks, or other supporting means may be provided, and utilized if desired, but a pair of pasters 19 have been found very desirable supports, which may be secured to any desired wall or a slab of marble merely by an adhesive. The pasters 19 each carry a ring 20 designed to be 40 engaged by a hook 21 secured to the back 18 by a paster 22. In this way the entire device may be quickly and easily mounted upon any surface without injuring the same and without requiring any holes to be drilled 45 in the wall, marble, or other support.
- The device is preferably placed in a vertical position, but of course may be arranged in any desired position. When properly mounted in the desired position and it is desired to remove one of the pieces of paper
- from pad 2, the thumbs are placed in notches 7 and 8 and pressed against the pad, after which the thumbs are moved toward end 12, the pressure thereof continuing. This will cause the top sheet of paper to be torn from 55 the clips 5 and be moved out slot 13 substantially as shown in Fig. 3. In this way it will be seen that the sheets of paper are vended or dispensed one at a time and with no one touching the paper except the person using the same.
- In order that the housing 1 may have a new pad arranged therein, the top 3 is preferably held in place by suitable corner members 23 and 24, pasted or otherwise secured 65 thereto, and to the sides of the housing. These members may be removed by cutting or in any desired manner, and new ones substituted whenever a new pad is placed in position. It will also be evident that if the 70 housing is made of wood, tin or other material, a lock or any other securing means could be substituted for the strips 23 and 24, without departing from the spirit of the invention.
- Having thus described my invention I claim as new and desire to secure by Letters Patent:—
- In a paper dispensing device, a housing for a paper pad formed with a slot at one 80 end through which the sheets of paper of said pad are designed to be drawn individually, means arranged on the opposite edge of said housing to said slot for retaining said pad in said housing, and a paper retaining spring secured to said housing, said spring being bent over so as to extend substantially parallel with said upper face of 85 said pad and having one end slidingly engage said pad so as to prevent the buckling of the lower part thereof as the various sheets of paper are drawn through said slot.
- In testimony whereof I have signed my name to this specification in the presence of two subscribing witnesses.
- ALBERT F. LESLER.
